UNITED STATES PATENT OFFICE.

FRED C. OLIN, OF BUFFALO, NEW YORK.

GOVERNOR FOR GAS-ENGINES, &c.

984,439.

Specification of Letters Patent. Patented Feb. 14, 1911.

Application filed April 29, 1908. Serial No. 429,839.

To all whom it may concern:

Be it known that I, FRED C. OLIN, a citizen of the United States, residing at Buffalo, in the county of Erie and State of New 5 York, have invented a new and useful Improvement in Governors for Gas-Engines, &c., of which the following is a specification.

This invention relates to a governor which is more particularly designed for controlling 10 the supply valve of a gas or other hydro-carbon engine according to the speed of the same but which may also be used for regulating the supply valve of an engine which is driven by another motive agent.

15 The object of this invention is to provide a governor for this purpose which is comparatively simple in construction, reliable in operation and easy of adjustment; which is so constructed that it is sensitive when 20 driven by a slow moving member, and which prevents sudden variations in the load upon the engine from producing an unduly quick change in the position of the supply valve of the same.

25 In the accompanying drawings consisting of 3 sheets: Figure 1 is a vertical longitudinal section of my improved governor. Fig. 2 is a fragmentary horizontal section of the same on line 2—2, Fig. 1. Fig. 3 is a fragmentary top plan view thereof. Figs. 4, 5 and 6 are vertical cross sections in the correspondingly numbered lines in Fig. 1.

Similar letters of reference indicate corresponding parts throughout the several 35 views.

A represents a hollow driving shaft of a governor which may be operatively connected with any suitable rotating part of the engine which is to be regulated. As shown 40 in Fig. 1, this shaft is arranged horizontally and journaled in bearings *a*, *a* rising from a base *B*, but if desired this shaft may be otherwise arranged to suit the particular construction of the engine to which it is applied.

C represents a valve rod which is arranged axially within the driving shaft and which is connected in any suitable manner with the gas supply or other valve which 50 controls the engine.

D represents a longitudinally movable shifting sleeve mounted on the periphery of the driving shaft and connected with the valve rod by a transverse pin *d* passing

through a longitudinal slot *e* in the driving 55 shaft. By this means the valve rod and shifting sleeve are compelled to turn with the driving shaft but are free to move lengthwise of the shaft independent thereof to an extent equal to the length of the slot *e* 60 in the driving shaft.

F represents a supporting sleeve which turns with its central part on the shifting sleeve while its reduced front part turns upon the driving shaft in front of the shifting sleeve. This supporting sleeve is rotated about the driving shaft and in the same direction but at a higher speed by means of a driven pinion *g* mounted on the driving shaft in rear of the supporting 70 sleeve and secured at the front end of its hub to the rear end of the supporting sleeve by set screws *g*¹, an intermediate gear wheel *h* meshing with the driven pinion, an intermediate pinion *i* connected with the intermediate gear wheel and journaled upon a stationary arbor *I*, and a driving gear wheel *J* secured to the driving shaft in rear of the driven pinion and meshing with the intermediate pinion. The arbor *I* may be supported in any suitable manner but preferably by the upper end of a bracket *K* which has two lower legs *l*, *l* engaging with sockets or recesses *l*¹, *l*¹ in the upper side of the base 80 *B* while its central part is provided with an opening *m* which receives the hub of the driving gear wheel and is held in place thereon between the rear side of the driving gear wheel and a screw nut *m*¹ applied to the rear end of its hub, as shown in Figs. 1 85 and 2.

On opposite sides of its rear end the supporting sleeve is provided with laterally projecting arms *N* which are preferably formed integral therewith. On the outer 95 end of each of these arms is pivoted an elbow-shaped governor lever having an inwardly projecting rear or inner arm *o* and a forwardly projecting front arm *o*¹.

The inner arms of the elbow levers are 100 operatively connected with the shifting sleeve *D* so that the latter and the valve rod are compelled to move with the inner arms in a direction lengthwise of the driving shaft but said arms and the parts connected therewith are free to rotate about the driving shaft, shifting sleeve and valve rod. 105 The connection between the inner arms of

the elbow levers and the shifting sleeve shown in the drawings consists of a ring P which is provided on diametrically opposite sides with recesses p which receive the inner 5 ends of the inner arms of the elbow levers. The bore of this ring engages with the periphery of a coupling sleeve Q mounted on the driving shaft while its front edge engages with the rear end of the shifting 10 sleeve and its rear edge engages with a flange q on the coupling sleeve, the front end of the coupling sleeve being connected by a screw joint with the rear end of the shifting sleeve. The coupling sleeve and its flange 15 together with the shifting sleeve thus form an annular groove in which the ring P is free to turn independently of the coupling and shifting sleeves while, nevertheless, it is compelled to move axially with the coupling 20 and shifting sleeves.

R , R^1 represent two governor weights which are arranged on diametrically opposite sides of the central part of the supporting sleeve and each of which is pivoted on 25 the front end of the front arm of the elbow lever on the same side of the driving shaft. When the governor is at rest the governor weights engage each other with their opposing inner sides for which purpose these 30 weights are recessed or bifurcated on their inner sides so that each weight can straddle the supporting sleeve, as shown in Fig. 6. While the governor is in operation the weights move radially inward and outward 35 relatively to the driving shaft and during this movement the weights are guided relatively to each other for keeping the same in alinement. The guide device for this purpose preferably consists of two guide rods 40 r , r' of tubular form arranged parallel to each other on opposite sides of the driving shaft and each secured at one end in an opening r^1 in one of the weights while its opposite end slides in an opening r^2 in the 45 other weight. The fast end of each guide rod r is preferably secured to its respective weight by a screw s and the extent of the sliding movement of the other end of this rod with reference to its weight is limited 50 by means of a screw s^1 secured to the last mentioned weight and projecting into a longitudinal slot s^2 formed in the sliding end of the guide rod r , as shown in Fig. 6.

The governor weights are yieldingly held 55 in their innermost position by a spring tension device which preferably consists of two swivels or heads T each of which is pivoted to the inner arm of one of the elbow levers and is provided with a flange t forming a 60 forwardly facing shoulder, a guide u of tubular form secured to each swivel head and projecting forwardly therefrom parallel with the driving shaft and into the recess or bifurcation of the weight on the same side 65 of the driving shaft, a coil-shaped governor

or return spring V surrounding each guide tube u and bearing at its rear end against the shoulder on the companion swivel head and an abutment disk W movable axially on the reduced front end of the supporting 70 sleeve and engaging with the front ends of both return springs, and an adjusting screw w engaging with the front side of the abutment disk and working on an external screw thread formed on the reduced front end of 75 the supporting sleeve. By screwing the nut w forwardly or backwardly on the supporting sleeve the tension of the governor springs may be reduced or increased for varying the resistance which they offer to the 80 outward movement of the governor weights.

Upon rotating the driving shaft motion in the same direction at an increased speed is transmitted to the supporting sleeve by means of the transmitting gears g , h , i , J . 85 During this rotation of the supporting sleeve the governor weights fly outwardly by centrifugal force and carry the front arms of the elbow levers in the same direction while their inner or rear arms move 90 lengthwise of the driving shaft, whereby the shifting sleeve and the valve rod are also moved forwardly lengthwise of the driving shaft and the valve connected with the valve rod is closed more or less. While the governor weights are thus thrown outwardly 95 the springs V are compressed but when the speed of the driving shaft is reduced these springs expand and operate to turn the elbow levers in the direction for moving the 100 governor weights inwardly and also causing the valve rod to be moved rearwardly for opening the regulating valve to a greater extent.

In order to prevent the governor from responding too suddenly when the load upon the engine is changed quickly, a retarding device is provided which preferably consists of two pistons or plungers x sliding in the 105 guide tubes r , heads x^1 closing those ends of the guide tubes r which are secured to the governor weight R^1 , and a piston or plunger rod y arranged in each guide tube r and secured at its inner end to the piston therein 110 while its outer end is secured to a bracket 115 or arm z fixed on the adjacent part of the governor weight in which the free end of the guide tube r slides, as shown in Fig. 6.

If there is a sudden reduction in the load upon the engine the tendency to suddenly 120 increase its speed is prevented by the resistance which is offered to the outward movement of the governor weights by the vacuum which is produced in the inner ends of the 125 guide tubes r as the plungers are drawn out of the same. A sudden increase of the load upon the engine is also prevented from causing the same to too suddenly decrease its speed owing to the resistance which is offered by the imprisoned air to the inward 130

movement of the governor weights as the plungers α move toward the front or closed ends of the guide tubes r .

My improved governor is exceedingly compact in construction and therefore especially desirable where but a limited amount of space is available, the several parts are so constructed and arranged that the same is not liable to get out of order and it effects a steady regulation of the valve which controls the motive agent of the engine, thereby rendering the same especially suitable for use where steady running of the engine is desirable.

15 By arranging the springs V lengthwise between the weights and the supporting sleeve and connecting the same with the inner or rear arms of the governor levers, it is possible to use springs which are comparatively long and of large diameter with a minimum amount of movement during the regulating operation, thereby causing the springs to be more active and rendering the tension of the same more uniform in different positions of the weights.

I claim as my invention:

1. A governor comprising a hollow driving shaft, a valve rod movable lengthwise in said shaft, a shifting sleeve mounted on the outer side of said shaft and connected with the valve rod, a governor lever having one arm connected with said shifting sleeve, a governor weight connected with the other arm of said lever, a rotatable driving sleeve surrounding the shifting sleeve and shaft and supporting said lever, means which rotate said driving sleeve from said shaft, a governor lever operatively connected with the shifting sleeve so as to be compelled to move therewith lengthwise of said shaft but be free to rotate about said shaft independent of said sleeve, and a governor weight pivoted on said lever.

2. A governor comprising a hollow driving shaft, a valve rod movable lengthwise in said shaft, a shifting sleeve mounted on the outer side of said shaft and connected with the valve rod, a governor lever having one arm connected with said shifting sleeve, a governor weight connected with the other arm of said lever, a rotatable support for said lever, and means for rotating said support from said shaft and connected with said valve rod, a governor lever operatively connected with the shifting sleeve so as to be compelled to move therewith lengthwise of said shaft but be free to rotate about said shaft independent of said sleeve, said connection consisting of a ring having a recess which receives one arm of said lever and which engage at one edge with the end of said shifting sleeve and a coupling which is engaged on its periphery by the bore of said ring and which is connected at one end with said sleeve while its opposite end is pro-

vided with a flange engaging with the other edge of said ring, a governor weight connected with said lever, a support for said lever rotatable about said shaft, and means for rotating said support from said shaft. 70

3. A governor comprising a driving shaft, a valve rod movable lengthwise of said shaft, a governor lever operatively connected with the valve rod, a governor weight connected with said lever, a support for said lever rotatable about said shaft, and means for rotating said support from said shaft at an increased speed. 75

4. A governor comprising a hollow driving shaft, a valve rod movable lengthwise 80 in said shaft, a shifting sleeve mounted on the outer side of said shaft and connected with the valve rod, a governor lever having one arm connected with said shifting sleeve, a governor weight connected with the other 85 arm of said lever, a rotatable support for said lever, and means for rotating said support from said shaft consisting of a driven pinion connected with said support, an intermediate gear wheel meshing with the 90 driven pinion, an intermediate pinion connected with the intermediate gear wheel, and a driving gear wheel secured to said shaft and meshing with said intermediate pinion. 95

5. A governor comprising a hollow driving shaft, a valve rod movable lengthwise in said shaft, a shifting sleeve mounted on the outer side of said shaft and connected with the valve rod, a governor lever having one arm connected with said shifting sleeve, a governor weight connected with the other arm of said lever, a rotatable support for said lever, and means for rotating said support from said shaft consisting of a driven 100 pinion connected with said support, an intermediate gear wheel meshing with the driven pinion, an intermediate pinion connected with the intermediate gear wheel, and a driving gear wheel secured to said 105 shaft and meshing with said intermediate pinion and a stationary bracket having an arbor upon which said intermediate pinion and gear wheel are journaled and a perforated part which receives the hub of the 110 driving gear wheel and engages on one of its sides with the latter, and a screw nut arranged on the hub of the driving gear wheel and engaging with the other side of said bracket. 115

6. A governor comprising a hollow driving shaft, a valve rod movable lengthwise in said shaft, a shifting sleeve mounted on the outer side of said shaft and connected with the valve rod, a governor lever having one arm connected with said shifting sleeve, a governor weight connected with the other arm of said lever, a supporting sleeve rotatable about said shaft and having an arm 125 on which said lever is pivoted, and means 130

for rotating said supporting sleeve from said driving shaft.

7. A governor comprising a hollow driving shaft, a valve rod movable lengthwise in said shaft, a shifting sleeve mounted on the outer side of said shaft and connected with the valve rod, a governor lever having one arm connected with said shifting sleeve, a governor weight connected with the other 10 arm of said lever, a supporting sleeve rotatable about said shaft and shifting sleeve and having an arm on which said lever is pivoted, means for rotating said supporting sleeve from said driving shaft, and a spring 15 interposed between said lever and said supporting sleeve and operating to turn the same in the direction for moving the weight toward said shaft.

8. A governor comprising a hollow driving shaft, a valve rod movable lengthwise in said shaft, a shifting sleeve mounted on the outer side of said shaft and connected with the valve rod, a governor lever having one arm connected with said shifting sleeve, 25 a governor weight connected with the other arm of said lever, a supporting sleeve rotatable about said shaft and shifting sleeve and having an arm on which said lever is pivoted, means for rotating said supporting 30 sleeve from said driving shaft, a spring arranged at the side of the driving shaft and operating at one end on said lever, and an abutment engaging the opposite end of said spring and adjustably mounted on said supporting sleeve.

9. A governor comprising a hollow driving shaft, a valve rod movable lengthwise in said shaft, a shifting sleeve mounted on the outer side of said shaft and connected with 40 the valve rod, a governor lever having one arm connected with said shifting sleeve, a governor weight connected with the other arm of said lever, a supporting sleeve rotatable about said shaft and shifting sleeve 45 and having an arm on which said lever is pivoted, means for rotating said supporting sleeve from said driving shaft, a spring operating at one end on said lever, an abutment disk engaging with the opposite end of the 50 spring and movable lengthwise on the supporting sleeve, and a screw nut arranged on the supporting sleeve and engaging said abutment disk.

10. A governor comprising a hollow driving shaft, a valve rod movable lengthwise in said shaft, a shifting sleeve mounted on the outer side of said shaft and connected with the valve rod, a governor lever having one arm connected with said shifting sleeve, 55 a governor weight connected with the other arm of said lever, a supporting sleeve rotatable about said shaft and having an arm on which said lever is pivoted, means for rotating said supporting sleeve from said 60 driving shaft, a swivel pivoted on the lever, 65

a spring bearing at one end against said swivel, and an abutment on the supporting sleeve bearing against the other end of said spring.

11. A governor comprising a hollow driving shaft, a valve rod movable lengthwise in said shaft, a shifting sleeve mounted on the outer side of said shaft and connected with the valve rod, a governor lever having one arm connected with said shifting sleeve, a 70 governor weight connected with the other arm of said lever, a supporting sleeve rotatable about said shaft and having an arm on which said lever is pivoted, means for rotating said supporting sleeve from said driving shaft, a swivel pivoted on the lever, 75 a guide connected with said swivel, a spring surrounding said guide and bearing at one end against said guide, and an abutment on said supporting sleeve bearing against the 80 other end of said spring.

12. A governor comprising a driving shaft, a valve rod movable lengthwise of the driving shaft, a pair of governor levers arranged on opposite sides of the shaft and 90 operatively connected with the valve rod, means for rotating said levers from the driving shaft, governor weights pivoted on said levers, and means operating to maintain said weights in alinement comprising a guide 95 rod secured at one end to one of said weights and sliding in an opening in the other weight, and means for limiting the separation of said weights consisting of a screw arranged on the weight in which said rod 100 slides and engaging with a longitudinal slot in the sliding part of said rod.

13. A governor comprising a driving shaft, a valve rod movable lengthwise of the driving shaft, a pair of governor levers arranged on opposite sides of the shaft and 105 operatively connected with the valve rod, means for rotating said levers from said driving shaft, governor weights arranged on said levers, and means for retarding the 110 separation and approach of said weights.

14. A governor comprising a driving shaft, a valve rod movable lengthwise of the driving shaft, a pair of governor levers arranged on opposite sides of the shaft and 115 operatively connected with the valve rod, means for rotating said levers from said driving shaft, governor weights arranged on said levers, and means for retarding the separation and approach of said weights consisting of a tube secured to one of said weights and having a head at one end and a plunger arranged in said tube connected with the other weight.

15. A governor comprising a driving shaft, a valve rod movable lengthwise of the driving shaft, a pair of governor levers arranged on opposite sides of the shaft and 120 operatively connected with the valve rod, means for rotating said levers from said 130

driving shaft, governor weights arranged on said levers, and means for retarding the separation and approach of said weights consisting of a tube closed at one end and secured at its closed end to one weight and sliding at its other end in the other weight, and a plunger arranged in said tube and connected with the other weight.

16. A governor comprising a hollow driving shaft, a valve rod sliding lengthwise in the shaft, a supporting sleeve rotatable about said shaft, means for rotating said sleeve from the shaft, governor levers piv-

oted on opposite sides of said sleeves, governor weights connected with said levers and having their inner opposing sides bifurcated or recessed, and return springs arranged in bifurcated or recessed parts of said weights and each operatively connected at opposite ends with one of said levers and said sleeve.

Witness my hand this 27th day of April, 1908.
